INSECT REPELLENT

Anthony G. Grady, Chicago, Joseph A. Verdol, Dolton, and Russell W. Walker, Lansing, Ill., assignors, by mesne assignments, to Sinclair Research, Inc., New York, N.Y., a corporation of Delaware
No Drawing. Filed Feb. 8, 1961, Ser. No. 87,782
10 Claims. (Cl. 167—22)

The present invention relates to the repelling of insects by using certain oxidized petroleum derivatives. According to this invention, it has been found that an alkylate boiling primarily in the range of about 100 to 460° F. when oxidized with a free-oxygen-containing gas, is a very effective insect repellent, particularly for cockroaches.

The alkylate used in the present invention boils primarily in the range of about 100° F. to 460° F. and generally has a boiling point spread of at least about 30° F. and preferably at least about 70° F. The alkylate is prepared from an isobutane and a C₃—C₄ aliphatic monoolefin hydrocarbon by treatment with a catalyst, for instance, an acidic material such as sulfuric acid, hydrofluoric acid or other mineral acids. The products produced by this alkylation process are essentially iso-paraffinic in structure and contain few, if any, olefin and aromatic components. The lower boiling components produced by the alkylation process, e.g. those boiling primarily in the range of about 100° F. to 350° F. are widely used in aviation fuels and premium automobile fuels, and are marketed as "alkylate gasoline." The "alkylate gasoline" fractions are suitable for use in preparing the repellent of the present invention. It is preferred, however, to employ the higher boiling fraction of the alkylate product, namely those boiling primarily in the range of about 350° to 460° F., which are known in the petroleum industry as "odorless solvents." "Odorless solvents" are currently marketed in two grades differing mainly in boiling range. The material marketed as odorless solvent light has an ASTM boiling range of about 345° F. to 395° F. with a 50% point of about 360° F. The odorless solvent heavy has a boiling range of about 375 to 460° F., and a 50% point of about 395° F. The olefin content of these products normally varies from about 1% to 10% and the total paraffin content is normally greater than about 90%.

The oxidized alkylate product of the present invention

2

ature range employed for oxidation can be from ambient temperatures to the reflux temperatures of the alkylate material employed when conducting the oxidation in the liquid phase. Preferably the temperature is from about 50 to 200° C. If a vapor phase oxidation procedure is employed, then the reaction is, of course, carried out above the boiling point of the alkylate feed and up to just below the decomposition temperature of the feed or product. The amount of oxygen employed in the oxidation can conveniently range from about 0.05 to 1 s.c.f./liter of hydrocarbon/hour and the reaction is continued for at least about 2 up to about 100 or somewhat more hours, preferably about 20 to 40 hours. Longer times can be used but do not seem to improve the product sufficiently to justify the added expense and inconvenience. The preferred manner of producing the repellents of the present invention is by non-catalytic liquid phase oxidation of the alkylate materials. Catalytically oxidized alkylate is found to be less effective as a repellent than alkylate oxidized in the absence of a catalyst.

The extent of oxidation effected is preparing the repellent of the present invention is measured by peroxide number. The non-catalytic oxidation is sufficient to provide the oxidized alkylate with a peroxide number of at least about 50, preferably at least about 200 or 400. No reason has been found for carrying the oxidation past a peroxide number of about 600. In catalytic oxidation the reaction is continued until a comparable amount of oxygen has been consumed or absorbed but a corresponding increase in peroxide number may not be apparent.

If desired, the oxidized alkylate of the present invention may be caustic washed as, for instance, with dilute solutions of alkali metal hydroxides to remove the foul odor of the oxidized alkylate. Caustic washing has been found to give no detrimental effect to the repelling properties of the oxidized alkylate of the present invention.

The following examples are included to further illustrate the present invention.

EXAMPLE I

Various samples of commercial odorless solvent heavy were submitted for cockroach repellency tests. Odorless solvent heavy is the fraction of the alkylate product of isobutane and butylene which boils primarily in the range of about 375 to 460° F. with a 50% point of about 395° F. The identity and results of the tests on the samples are shown in Table I.

Table I.—Identity of Odorless Solvent Samples In Cockroach Repellency Tests

Sample	Nature of odorless solvent heavy	Saponification number	Peroxide number	Bromine number	Odor	Relative repellency
A.....	Unoxidized.....	0	9.5	7.7	Poor.....	Poor.
B.....	Portion of A treated with NaIco HA alumina.....	0	0.6	5.7	Nil.....	Do.
C.....	Unoxidized.....	0	0.7	27.0	do.....	Do.
D.....	Portion of C oxidized with oxygen at 100° C. without catalyst.....	28.8	382	12.3	Foul.....	Good.
E.....	Portion of C oxidized in presence of cobalt naphthenate at 100° C.....	46.1	31.7	6.5	Sweet pleasant..	Fair.

is obtained as aforementioned by subjecting the alkylate material to oxidation with a free oxygen-containing gas. The alkylate may be converted by non-catalytic or catalytic oxidation of the alkylate in the liquid or vapor phase through intimate contact with a free oxygen-containing gas. In general, the oxidation of the alkylate material is carried out with molecular oxygen-containing gases such as air, pure oxygen, or their mixtures at atmospheric or superatmospheric pressures. The temper-

65 Samples A and C were unoxidized alkylate as established by their low peroxide number.

Sample D was prepared by oxidizing a portion of Sample C as follows:

Oxidation apparatus was set up and consisted of a steam jacketed glass tube approximately 36" long and 1 1/2" wide. The bottom of the tube was equipped with a removable section fitted with a 50/50 standard taper joint containing a porous plate. Below the porous plate

there was located an inlet stopcock for the introduction of oxygen and a second drain stopcock for removing the product. The top of the reactor tube was fitted to a cold water condenser by means of a 24/40 standard taper joint.

The reactor was charged with 500 grams of sample C and steam was introduced through the jacket until the reaction temperature of 100° C. was attained. Oxygen was then bubbled through the system at a rate of about 0.3 ft.³/hour. Oxidation was carried out for about 30-40 hours to obtain a product showing a peroxide number of about 382. The course of the oxidation reaction could be followed by measuring the peroxide number of samples of the reaction mixture taken over the reaction period.

Sample E was prepared adding 10 grams of cobalt naphthenate to 575 grams of sample C and the mixture was heated to 165° C. Oxygen was passed through the mixture at a rate of 0.5 ft.³/hour for a period of 6 hours. The resulting product showed the following properties: peroxide No. 31.7; saponification No. 46.1; bromine No. 6.5. The product had a sweet ester odor in contrast to

tory Chow was placed in the center of each test pan. One hundred German cockroaches were introduced into one pen and fifty American cockroach nymphs were introduced into the other.

Controlled lighting was provided during the test period. From 6:00 a.m. to 6:00 p.m. each day the pen was lighted by fluorescent lights suspended 18" above the pen. From 6:00 p.m. until 6:00 a.m. the pen was in darkness and during this time the cockroaches would seek food and water. With the beginning of each light cycle the cockroaches would seek refuge from the light in the shelter cartons, unless repelled by the treated linings.

The relative repellency of the various treatments was determined by recording the number of cockroaches inhabiting each shelter at 8:00 a.m. each day. Counts were facilitated by removing the cartons from the test pen and immobilizing the cockroaches with CO₂. All cartons and cockroaches were returned to the test pan after counting. Any dead or moribund insects were replaced each day with fresh insects.

The results of these repellency test conducted over a period of eight days are summarized in Table II below.

the material prepared by oxidation of odorless solvent heavy without catalyst (sample D).

The cockroach repellency tests were carried out according to the procedure described below.

Test insects: Adult male German cockroach, *Blattella germanica* (L.). Thirteen-week-old American cockroach nymphs, *Periplaneta americana* (L.).

Test pan: The test pan consisted of a 40" x 24" x 8" stainless steel open top box, partitioned in the center to form two 20" x 24" pans. Petrolatum was applied to the walls of the pen to prevent the escape of the test insects.

Test shelter: One-half pint ice cream type cardboard containers the bottom section of which were lined with treated 15 cm. No. 2 filter papers and the lid section with 9 cm. No. 2 filter paper and an entry hole through the wall and lining of each carton was provided in the base.

Procedure.—The test samples were applied to the filter paper shelter liners by pipetting 1.3 ml. of each onto the 15 cm. discs and 0.5 ml. onto 9 cm. discs while on glass plates. When the filter paper had dried to touch, they were pressed into the bottom and lid sections of the cardboard cartons to form a continuous treated interior surface lining. Four cartons were prepared for each test sample, two of which were used in tests conducted with German cockroaches and two with American cockroaches.

The duplicate test shelters of each treatment were placed on the floor of the respective pans in random fashion. Water and food in the form of Purina Labora-

45 The data of Tables I and II establish that the unoxidized alkylate showed little, if any, repellency towards cockroaches whereas oxidized samples of this material were effective as repellents. The data also demonstrate that the oxidized alkylate was much more effective when oxidized in the absence of a catalyst than when oxidized 50 catalytically.

EXAMPLE II

Oxidized alkylate was prepared both by oxidation in 55 the absence of catalyst (sample F) and in the presence of a cobalt naphthenate catalyst (sample G) in accordance with the general method of Example I and submitted to cockroach repellency tests. The alkylate oxidized was prepared from isobutane and butene and boiled primarily in the range of 375 to 460° F. with a 50% point of about 395° F. and is known as odorless solvent heavy. For comparative purposes, a commercial repellent designated as X at 1% concentration in base oil (sample H) and a 2% concentrate of fatty acids extracted from alkylate in the same base oil were also tested. The fatty extract of oxidized alkylate was prepared by treating the oxidized material with dilute NaOH and acidifying the aqueous alkali extract. The extract was washed with ether and the ether evaporated. The resulting acid residue was blended into the base oil at a concentration of 2%. The 2% concentrate showed a peroxide No. of 3.2, sap. No. of 5.9 and bromine No. 32.3. The material had a foul odor and was designated sample I. A summary of materials submitted for testing and the results are presented in Table III.

Table III.—Identity of Odorless Solvent Samples and Commercial Repellent Submitted for Cockroach Repellency Tests

¹ 2,3,4,5-bis-butylene tetrahydrofurfural, a condensation product of furfural and butadiene.

The procedure employed for the second series of repellency tests was essentially the same as described previously for the first series of tests, excepting that the filter papers wetted with the test samples were permitted to dry for 24 hours. This modification was made to reduce the mortality rate, since the earlier test indicated that the high mortality rate might be due to the presence of highly volatile material in the test samples. Four hundred adult male German cockroaches, *Blatella germanica* (L.) were used in the test pan. Any dead or moribund cockroaches were replaced each day with fresh insects. Results of these tests are shown in Table IV.

It should be noted that Table IV also includes a test exposure of four shelters each of samples F, H and untreated shelters. The age of this shelter treatment was 21 days. This separate test was run for the purpose of directly comparing the repellency of oxidized odorless solvent heavy with sample H. This separate test clearly established that the oxidized odorless solvent heavy sample F was superior to sample H.

The data of Tables III and IV demonstrate that the non-catalytically oxidized odorless solvent heavy was superior to the commercial repellent X when the commercial repellent was tested at a 1% concentration in base oil (sample H). The sample containing fatty acids

20 less solvency heavy of Example II (sample F). A 2% concentrate of commercial repellent X (sample J) was also tested. The identity of the materials tested and the results are summarized in Table V.

derived from the oxidized odorless solvent heavy proved ineffective as a repellent and indicated that the foul odor of oxidized odorless solvent was not responsible for its repellency.

EXAMPLE III

Various peroxides as concentrates in base oil (samples K, L, M) were submitted to the cockroach repellency tests of Example I and compared to the oxidized odor-

70 The procedure used for testing these samples was essentially identical with the procedure already described. The test was divided into two parts. Part I consisted of a four replicate test with samples F and J, using 250 adult male German cockroaches, *Blatella germanica* (L.). Part II consisted of a two replicate test with samples J through M, using 250 German cockroaches. The results of these tests are summarized in Table VI.

Percent mortality.....	0	0	0	10	5	9	8

Tables V and VI show that the odorless solvent heavy (non-catalyzed oxidation) was superior to the commercial repellent X when the latter was employed at 2% concentration (more than the recommended concentration for commercial use). The tests also show that tertiary alkyl peroxides and aryl peroxides were ineffective repellents, suggesting that if peroxide were responsible for the repellent properties of the oxidized alkylate they were more likely peroxides of a specific structure derived from the alkylate and not any peroxide selected randomly. There is also the possibility that other oxygenated compounds contribute to repellency.

EXAMPLE IV

Various samples identified in Table VII below were subjected to the cockroach repellency test. In preparing sample N an oxidized odorless solvent heavy having an initial peroxide No. of 226 washed twice with equivolume portions of 5% NaOH and then with water. The resulting product had a sweet, pleasant odor, and showed a peroxide number of 109. Samples O and P were prepared by the non-catalytic oxidation procedure described in Example I. For comparison, the test on oxidized odorless solvent F and the commercial repellent X, 2% conc. in base oil (J) are also included. The results are also summarized in Table VII.

Table VII.—Identity of Experimental Sample for Cockroach Repellency Tests

Sample	Identity of sample	Peroxide number	Odor	Relative repellency
F.....	Odorless solvent heavy oxidized without catalyst (see Table III). 2% X in base oil.....	293	Foul.....	Good.
J.....				
N.....	Oxidized odorless solvent, heavy, which was caustic treated to remove fatty acids, peroxyacids, etc.	109	Sweet pleasant.	Fair. Good.
O.....	C ₆ + naphtha reformate oxidized at 100° C. for 77 hours without catalyst.	575	Pleasant.....	Poor.
P.....	Propylene tetramer oxidized at 100° C. for 20 hours without catalyst.	402	Foul.....	Do.
Q.....	2.7% cumene hydroperoxide in base oil plus 1% iso-octyl aldehyde.	466	do.....	Do.

The test procedure was the same as already described. Two separate tests, three replicates each, were conducted using 250 adult male German cockroaches, *Blattella germanica* (L.). The results of these tests are presented in Table VIII.

Table VIII.—Evaluation of Oxidized Odorless Solvent Heavy and Related Materials for Repellency Against German Cockroaches

[Average percent inhabiting shelters]

Days after treatment	Test No. 1								
	2	3	4	5	6	8	9	15	
Sample:									
J.....	2	51	40	29	21	17	19	17	
O.....	0	1	9	24	27	24	18	19	
P.....	15	10	17	19	22	25	26	24	
Percent mortality.....	1	0	2	3	2	6	10	19	

Days after treatment	Test No. 2								
	2	3	4	5	6	8	9	15	
Sample:									
F.....	0	4	8	7	18	4	8	5	
N.....	0	3	5	17	13	8	14		
Q.....	78	65	60	49	41	46	47	46	
Percent mortality.....	0	0	1	6	8	10	13	29	

Test No. 1 (Table VIII) indicated that the oxidized propylene tetramer and reformate showed some repellency for the first five days, but after that time sample J shower greater repellency. Thus, these oxidized petroleum stocks do not appear to be effective repellents in comparison with oxidized odorless solvent.

Test No. 2 (Table VIII) showed that oxidized odorless solvent and the caustic washed oxidized odorless solvent were both good repellents. This further demonstrates that the acidic components, which presumably were responsible for the foul odor of oxidized odorless solvent heavy, were not active repellents.

The test sample Q containing isoctyl aldehyde and cumene hydroperoxide did not show any repellency whatsoever. Therefore, no advantageous effect was realized by adding aldehyde to cumene hydroperoxide since earlier tests in Table VI showed that cumene hydroperoxide per se was ineffective.

EXAMPLE V

Samples identified in Table IV below were subjected to the cockroach repellency test described in Example I.

Table IX.—Identity of Samples Submitted for Cockroach Repellency Tests

Sample	Identity	Saponification number	Peroxide number	Relative repellency
R.....	Odorless solvent heavy oxidized without catalyst to a peroxide number of 425.	58.1	425	Good.
S.....	Above sample diluted to 20% by volume in odorless solvent heavy.	12	67	Fair.
T.....	Heart cut obtained on distillation of odorless solvent heavy (B.P. 65° C./12 mm. to 80° C./0.28 mm.).	10.6	102.5	Poor.
U.....	Odorless solvent heavy oxidized to peroxide number of 101 (without catalyst).	2.23	101	Fair.
V.....	Caustic washed odorless solvent heavy (oxidized without catalyst).	17.0	237	Good.
W.....	Caustic washed oxidized odorless solvent heavy, which was treated with KI to destroy peroxides (original peroxide number was about 300 after oxidation without catalyst).	18.7	50	Do.
Y.....	Odorless solvent heavy oxidized with cobalt naphthalene catalyst plus 5% t-butyl perbenzoate.	70	575	Poor.

The tests were conducted in the same manner as described in Example I. The test was broken down into two parts with 250 cockroaches being used in each part 75 of the test. The results are summarized in Table X.

Table X.—Summary of Cockroach Repellency Tests

Percent dead and moribund	4	3	1	0	4	32	17	21	17	0	7.05	

According to the results summarized in part I above, the oxidized odorless solvent heavy (R) was almost completely effective as a repellent. The odorless solvent sample diluted to 20% concentration by volume (S) and the odorless solvent sample oxidized to a peroxide number of only 101 (U) were about equal in repellency, but were not as effective as the undiluted sample R. The heart cut obtained by distillation of odorless solvent heavy T showed poor repellency. Thus in general the active ingredient or ingredients were concentrated in the lower boiling components of the oxidized odorless solvent, especially since the higher boiling concentrate, as indicated, showed poor repellency.

Part II of the test presented in Table X above was designed in order to further evaluate the repellency oxidized odorless solvent, which was caustic treated to destroy the free acids and treated with potassium iodide to destroy most of the peroxides. The test showed that the caustic washed oxidized odorless solvent heavy V and the caustic washed sample which also had the majority of the peroxides removed (W) were almost equal in repellency. Sample Y was included in the test in order to ascertain whether or not a sample of odorless solvent heavy, which was oxidized with cobalt naphthenate catalyst, and which previously showed little repellency, could be made more repellent by the addition of an alkyl perester. The test results, however, indicated that this sample showed poor repellency.

We claim:

1. A method for producing a cockroach repellent which comprises oxidizing the alkylate product of isobutane and a C₃—C₄ aliphatic monoolefin, said alkylate product boiling primarily in the range of about 100 to 460° F. through

intimate contact with an oxidizing free oxygen-containing gas for a time to absorb sufficient oxygen to provide said alkylate product with a peroxide number at least about 50 up to about 600 under non-catalytic oxidation conditions, said time being up to about 100 hours.

2. The product produced by the method of claim 1.
3. The method of claim 1 wherein the oxidation is conducted in the liquid phase and in the absence of an oxidation catalyst.
4. The method of claim 3 wherein the alkylate product has a boiling range of about 350 to 460° F.
5. A method of claim 3 wherein the oxidation is conducted for a time sufficient to provide the alkylate produced with a peroxide number of at least about 200.
6. The product produced by the method of claim 5.
7. The method of claim 5 wherein the temperature of oxidation is about 50 to 200° C.
- 45 A method for repelling cockroaches from an area subject to cockroach encroachment which consists essentially of applying to said area the product produced by the method of claim 1.
9. A method for repelling cockroaches from an area subject to cockroach encroachment which consists essentially of applying to said area the product produced by the method of claim 3.
- 50 10. A method for repelling cockroaches from an area subject to cockroach encroachment which consists essentially of applying to said area the product produced by the method of claim 5.
